CLAIM

The ornamental design for a vented lid for covering a vessel containing food and/or fluids during storage and/or cooking, as shown and described.

DESCRIPTION

FIG. 1 is a bottom view of a lid showing my new design.

FIG. 2 is a top view of the lid of FIG. 1.

FIG. 3 is a right side view of the lid in FIG. 1. Left side view is identical to the right side view.

FIG. 4 is a front view of the lid in FIG. 1.

FIG. 5 is a rear view of the lid in FIG. 1.

FIG. 6 is a bottom perspective view of the lid in FIG. 1.

FIG. 7 is top perspective view of the lid in FIG. 1.

FIG. 8 is a bottom perspective environmental view of the lid in FIG. 1; and,

FIG. 9 is a top perspective environmental view of the lid in FIG. 1.

The broken lines showing a vessel, for example such as a glass or a bowl, and indicia are for environmental purposes only and form no part of the claimed design.
